UNITED STATES PATENT OFFICE.

GOTTHOLD HILDEBRANDT, OF SPANDAU-TIEFWERDER, NEAR BERLIN, GERMANY,
ASSIGNOR, BY MESNE ASSIGNMENTS, TO AMERICAN INDUSTRIAL GAS COMPANY,
OF NEW YORK, N. Y., A CORPORATION OF NEW YORK.

APPARATUS FOR LIQUEFYING GASES WITH A LOW BOILING-POINT.

1,199,700.

Specification of Letters Patent.

Patented Sept. 26, 1916.

Application filed January 9, 1911. Serial No. 601,614.

To all whom it may concern:

Be it known that I, GOTTHOLD HILDEBRANDT, engineer, citizen of Germany, subject of the King of Prussia and Emperor of Germany, residing at Spandau-Tiefwerder 29b, near Berlin, in the Kingdom of Prussia and Empire of Germany, have invented new and useful Improvements in Apparatus for Liquefying Gases with a Low Boiling-Point, of which the following is a specification.

The liquefaction of gases with a low boiling point has heretofore generally been effected only by the regenerative method indicated by Siemens in the year 1857 which consists in compressing, cooling and expanding these gases such for example as nitrogen, oxygen, hydrogen and so forth, and conducting the cooled gases thus obtained in counter current to fresh compressed gases, thereby producing an interchange of heat, which ultimately results in the desired liquefaction. In accordance with various systems this expansion has taken place either in a counter current system or pipes or in open cavities. This method has presented the defect that the liquefying period occupies a considerable time as the greatest cooling which is theoretically possible cannot be reached owing to the apparatus employed, because with this method of expanding, the frictional resistances of the counter current system of piping do not permit of fully utilizing the energy supplied in the compressed gases, and by this method it is impossible to utilize the kinetic energy of the gas molecules obtained by expanding to such an extent that their pressure falls below atmospheric pressure after the expansion.

It is well known that compressed gas when it issues through an aperture into a space of less pressure and escapes with an increased kinetic energy, is cooled close to the discharge aperture. This cooling (called by Travers "velocity cooling") has not been used up to the present time for the liquefaction or the separation of gas although it represents a very rich source of cold because this cooling exists only immediately after passing through the aperture and disappears at a relatively short distance from the aperture, the velocity of the stream of gas being reduced by friction caused by its impinging against the wall of the vessel

into which it flows. Therefore in order to produce low temperatures cooling by utilizing the Joule-Thompson effect only was applied which is the result of the internal work only caused by the expanding gas.

I have now succeeded in utilizing the velocity cooling for the continuous cooling and liquefaction of gases and the separation of gas mixtures by applying a particular form of expanding nozzle and the space into which the expanding gas stream flows.

The apparatus hereinafter described is designed to avoid the loss of energy which is present in existing systems, and to this end the expansion is effected in a space of gradually increasing cross-sectional area, for instance in one or more nozzles of the type evolved by Laval, the smallest and largest cross sections of these nozzles presenting such differences that the expansion of the gas in the nozzle chamber itself may fall below the pressure of the atmosphere.

In the accompanying drawings Figure 1 represents a longitudinal section of a simple form of apparatus embodying this invention; Fig. 2 is a similar view of another form with a device for transferring the cold to the compressed gas; Figs. 3 and 4 represent similar views of another form of the apparatus with an enlarged inlet space, a part of Fig. 4 being broken off for convenience in illustration.

In the drawings the preliminarily cooled compressed gas passes through the tube A and expansion valve B into the nozzle C. The nozzle C has a conical form of gradually increasing sectional area.

Taking the admission pressure of the preliminarily cooled compressed gas by way of example as 100 atmospheres equal to 100 kg. per square cm. and the admission aperture A of the nozzle C as 1 square mm. the velocity increases in correspondence with the diminishing pressure in the nozzle. The molecules then separate more and more from each other and when the width of the opening of the nozzle has reached 40 mm. that is to say presents a ratio to the admission aperture of 1 to 1250, the pressure of the gas has fallen to 800 grams per square cm., that is to say to a minus pressure of somewhat more than one-fifth of an atmosphere. It is therefore important that the lower aperture as compared with the upper

aperture of the nozzle should have a substantially larger cross section. The increase in cross section may be so large that starting at any desired initial pressure the gas is able 5 to expand to atmospheric pressure and below. When applying a nozzle of this construction there is a minus pressure in the gas itself which accelerates its liquefaction. By the conversion of the gas pressure into 10 the extremely high velocities obtained by nozzle expansion a large expenditure of external work is required so that the corresponding heat equivalent disappears and as the process takes place almost adiabatically 15 this is only at the cost of the temperature of a part of the expanded gas.

Rankine has already shown that the adiabatic expansion of superheated steam causes its condensation and in the Laval nozzle a 20 highly heated liquid is converted by cooling into a mixture of liquid and vapor. The present invention is based on similar physical principles. In the first place the specific heat of the expanded gas and the partitions 25 is consumed to cover the expenditure of heat, then as soon as the pressure falls below atmospheric pressure a part of the gas must yield up its latent heat, that is to say it liquefies, but at first these liquid particles 30 retain the velocities of the former gas molecules exactly like the steam condensate of a steam generator feed injector. It is an advantage of the system that this reduction of pressure below atmospheric pressure takes 35 place merely by an increase of the velocity of the molecules without the necessity for special air pumps. Thus it is possible to cause the nozzles to open into a collecting nozzle E (Fig. 2) or a collecting tube and to 40 convert the velocity into pressure without risk of the liquid obtained again vaporizing.

It is of course necessary by suitably forming the nozzle to prevent any friction of the gas at the nozzle walls when the gas passing therethrough is under higher pressures. 45 For this purpose the portion of the nozzle near its inlet end is enlarged, as diagrammatically shown in Figs. 3 and 4. At the inlet of the gas the expansion reservoir is 50 enlarged to a cylindrical space G so that the jet of the gas issuing from the valve B or the like does not touch the walls. In consequence of injector action or suction a vacuum is formed at the outer ends H of the enlarged space G, which assists the cooling action. 55 A purely adiabatic expansion is not possible because the metallic nozzle and the supply pipe conduct their heat to the expanded gas. In order to avoid this defect 60 the cold imparted to the expansion valve B is transferred by a device shown in Fig. 2 directly to the compressed gas before the expansion and not only cools it but its property of being a poor conductor of heat 65 is utilized for surrounding the expansion

nozzle with a gas envelop which is a poor conductor. With this object the nozzle C is made of a substance which is a good conductor such as copper, and inserted in a vessel D which receives the cooled compressed gas from the inlet (A). From the vessel D the cooled compressed gas is conducted to the expansion valve B, from which it is expanded into the conical nozzle C. This apparatus is likewise utilized for separating any foreign gases with a high boiling point from the compressed gas to be liquefied before it can exert any harmful effect by stopping the valve. The cooling which takes place during the expansion process in 70 the copper nozzle is consequently transferred directly to the compressed gas before its expansion and gradually cools it sufficiently to cause the foreign substances of higher boiling point as for instance water-vapor, carbonic acid, etc., contained in the compressed gas to be precipitated as liquid or solid bodies which can be drawn off 80 through a special pipe F in the bottom of the vessel D.

Having now described my invention what I claim and desire to secure by Letters Patent of the United States is:

1. In an apparatus for liquefying gases with a low boiling point, a conduit for the compressed and cooled gas, and an expansion nozzle arranged to receive the gas from said conduit and to expand and liquefy the same, said expansion nozzle having a cross-sectional area which gradually increases 95 substantially as the square of the distance from the point of admission of the gas, the ultimate dimensions of said area being small as compared to the length of the nozzle, and said nozzle being so proportioned as to effect velocity cooling of the gas expanding therein.

2. In an apparatus for liquefying gases with a low boiling point, a conduit for the compressed and cooled gas, and an expansion nozzle arranged to receive the gas from said conduit and to expand and liquefy the same, said expansion nozzle having an enlarged portion at its smaller end and being of gradually increasing cross-sectional area and being so proportioned as to effect velocity cooling of the gas expanding in said nozzle of gradually increasing area.

3. In an apparatus for liquefying gases with a low boiling point, a conduit for the compressed and cooled gas, an expansion nozzle arranged to receive the gas from said conduit and to expand and liquefy the same, and a vessel surrounding said nozzle for receiving the gas in its passage from said conduit to the inlet of the nozzle, said expansion nozzle being of gradually increasing cross-sectional area and being so proportioned as to effect substantially adiabatic expansion of the gas therein.

4. In an apparatus for liquefying gas with a low boiling point, an expansion nozzle of gradually increasing cross-sectional area, having a substantially smaller cross-sectional area at its inlet than its outlet, and being so proportioned as to effect substantially adiabatic expansion, said nozzle being of conical contour, and being provided with an enlargement near its inlet end.
5. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, a part of said conduit being arranged in a heat-conducting contact with the portion of said nozzle near the said expansion valve.
6. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, a part of said conduit being arranged in a heat-conducting contact with the portion of said nozzle near the said expansion valve.
- 10 5. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, and the conical nozzle being proportioned to effect velocity cooling of the gases expanding therein.
- 15 6. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, a part of said conduit being arranged in a heat-conducting contact with the portion of said nozzle near the said expansion valve.
- 20 5. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, and the conical nozzle being proportioned to effect velocity cooling of the gases expanding therein.
- 25 6. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, a part of said conduit being arranged in a heat-conducting contact with the portion of said nozzle near the said expansion valve.
- 30 5. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, and the conical nozzle being proportioned to effect velocity cooling of the gases expanding therein.
- 35 6. In an apparatus for liquefying gases with a low boiling point and in particular atmospheric air and hydrogen gas the combination of a conduit for the compressed and cooled gas, an expansion valve at the end of said conduit, with a conical nozzle of gradually increasing cross-sectional area in connection with said expansion valve, the admission aperture of said nozzle having a substantially smaller cross-section than the discharge aperture, a part of said conduit being arranged in a heat-conducting contact with the portion of said nozzle near the said expansion valve.

In testimony whereof I have hereunto set my hand in presence of two subscribing witnesses.
